**BARREL, FOREARM AND RECEIVER ASSEMBLY
MECHANISM FOR SHOTGUNS**

Ernest P. Simmons, Kansas City, Kans., assignor to Olin Mathieson Chemical Corporation, a corporation of Virginia

Application December 2, 1954, Serial No. 472,634

5 Claims. (Cl. 42—75)

This invention relates to new and useful improvements in shotguns, and has particular reference to the mechanism by means of which the barrel and forearm of the gun are detachably secured to the receiver portion of the gun.

In shotguns the barrel is ordinarily secured detachably to the receiver in order that it may be disassembled therefrom so that the gun may be stored in a shorter space for convenience in storage and transportation. In at least one typical gun, the barrel is secured in the gun receiver by a rotatably detachable connection such as a threaded joint, and is provided with a radially extending fixed arm. The forearm of the gun carries a take-down screw which threads into said arm, whereby both to secure the forearm to the barrel-receiver assembly, and to secure the barrel against accidental rotation. Also, said take-down screw may be provided with a smooth extension which projects into a socket formed in a part rigidly associated with the receiver, whereby the assembly is rendered still more rigid.

A disadvantage of this arrangement has been that with the barrel disassembled from the gun, there is nothing for the take-down screw to engage, the arm normally engaged thereby being attached to the barrel, so that the forearm cannot be retained in assembly with the receiver. This assembly is desirable, for the purposes of decreasing the number of pieces of the gun when the barrel is detached, protecting the forearm, which is normally wooden, against damage, and in an automatic gun of the split-chamber type, to protect the chamber member from damage. Said chamber member is relatively thin-walled and delicate, and projects forwardly from the receiver after the barrel has been removed. The forearm partially encloses and protects this chamber.

The principal object of this invention is, therefore, the provision in a gun of this type of means for securing the forearm to the receiver independently of its connection to the barrel.

Another object is the provision of a securing means of the general character described which engages the take-down screw to hold the forearm and which is entirely automatic, but which at the same time will not interfere in any way with the normal threaded engagement of said screw with the barrel arm.

Other objects are simplicity and economy of construction, efficiency and dependability of operation, and adaptability to be applied to pre-existing guns with a minimum of alteration.

With these objects in view, as well as other objects which will appear in the course of the specification, reference will be had to the accompanying drawing, wherein:

Fig. 1 is a fragmentary, longitudinal mid-sectional view of a shot gun embodying the present invention, with parts left in elevation and partially broken away.

Figs. 2, 3 and 4 are enlarged sectional views taken respectively on lines II—II, III—III and IV—IV of Fig. 1.

2

Fig. 5 is a fragmentary sectional view taken on line V—V of Fig. 4.

Like reference numerals apply to similar parts throughout the several views, and the numeral 2 applies to the receiver or body portion of the shotgun, said receiver being shown only fragmentarily. The gun barrel 4 is detachably connected at its rearward end into the receiver, as by threaded connection 6. Said threads may be standard, but more commonly are of the "bayonet" type, so that full engagement thereof is obtained by only a partial revolution of the barrel about its axis. A tubular chamber member 8 is mounted in and carried by the receiver, but extends forwardly into the rearward portion of the barrel as shown, and extends forwardly from the receiver when the barrel is detached. It is adapted to carry a shell 10 in firing position. Additional shells 10 are carried in a magazine tube 12 disposed beneath and parallel to barrel 4, and secured rigidly at its rearward end into the receiver. The shells in said magazine are urged rearwardly into the receiver by a follower cup 14 slidable in the magazine tube and urged rearwardly by a compression spring 16 disposed in said tube, said spring abutting at its rearward end against said cup and at its forward end against a cylinder plug 18 closing the forward end of said tube and secured therein by a pin 20 extending diametrically through said plug and tube, as best shown in Fig. 2. The shells fed from the magazine tube to the receiver are elevated successively to firing position in chamber 8 by a mechanism not shown and forming no part of the present invention.

An arm 22 is welded or otherwise rigidly fixed to barrel 4, and extends radially downwardly therefrom in spaced apart relation from the forward end of magazine tube 12. A forearm 24, which is usually wooden, encloses the magazine tube and extends forwardly therefrom. Said forearm is provided with a longitudinal bore 26 which fits slidably over the magazine tube, the forearm being slid rearwardly over the tube from the forward end thereof. Said forearm has a slot 28 formed longitudinally therein between bore 26 and the top thereof, whereby to permit passage of the forearm over barrel arm 22. The rearward end of the forearm abuts the forward end of the receiver in a tongue-and-groove connection indicated at 30. The upper edge of the forearm is channelled to the contour of the barrel, and partially encloses the same.

A take-down screw 32 is disposed beneath and parallel to barrel 4, being mounted for rotation and axial sliding movement in the forwardly extended portion of forearm 24. Said screw is provided at its forward end with a knurled head 34 which cooperates with the forward end of the forearm, a lock washer 36 being interposed therebetween. Adjacent its rearward end, the threaded portion 38 of the screw is adapted to be threaded into a tapped bore provided therefor in barrel arm 22. A snap ring 40 engaged in a groove 42 formed peripherally in the screw just forwardly of its threaded portion serves to prevent accidental forward withdrawal of the screw from the forearm. The extreme rearward end portion 44 of the screw-rod is of reduced diameter and fits slidably into a bore 46 formed therefor in plug 18 of the magazine tube. It is disposed eccentrically above the axis of said plug, and engages a notch 48 (Fig. 2) formed in the upper edge of pin 20, whereby to prevent accidental movement of said pin.

The rearward portion of screw-rod 32 has a V-shaped groove 50 formed peripherally therein within plug 18. Said plug has a narrow slot 52 formed transversely therein. As best shown in Fig. 3, said slot extends approximately half way through the plug, and intersects

bore 46 thereof in registering relation with groove 50 of the screw-rod. Disposed in said slot is a spring 54 formed of a length of resilient wire formed in generally V-form. One leg 56 thereof is curved and bears against the inner surface of the magazine tube, and the other leg 58 bears against the base of slot 52 and in the groove 50 of the screw-rod.

When the gun is fully assembled as shown, the engagement of take-down screw 32 in barrel arm 22 urges forearm 24 rearward firmly against the receiver. Also, the barrel is thereby locked positively against rotation, so that the barrel cannot be turned to free it from the receiver. To remove the barrel, the operator first turns the knurled head 34 of take-down screw 32 sufficiently to disengage the threaded portion 38 thereof from barrel arm 22, after which the forearm 24 is slid forwardly off of the magazine tube. The barrel may then be rotated to disengage the threaded connection 6 thereof from the receiver. To reassemble the forearm with the receiver, the bore 26 of the forearm is slid over magazine tube 12, and the take-down screw is pushed rearwardly to force the rearward end portion 44 thereof into bore 46 of plug 18. The forward end of the take-down screw is tapered to facilitate its entry past spring 54. Arm 58 of the spring then snaps into groove 50 of the take-down screw, acting as a detent whereby the take-down screw is held releasably in plug 18, and forearm 24 is maintained in assembly with the receiver portion of the gun. It will be noted that spring arm 58 engages the rearward sloping face of V-groove 50, thereby camming the take-down screw rearwardly to hold the parts snugly in assembly. When the barrel is assembled in the gun, spring 54 exerts a frictional load on the take-down screw tending to prevent loosening of said screw by shaking or vibration.

Although I have shown and described a specific embodiment of my invention, it will be readily apparent that many minor changes of structure and operation could be made without departing from the spirit of the invention as defined by the scope of the appended claims.

What I claim as new and desire to protect by Letters Patent is:

1. In a shotgun, the combination of a receiver, a removable barrel connected at its rearward end in said receiver by a rotatably detachable connection, a magazine tube fixed in said receiver and extending forwardly beneath and parallel to said barrel, an arm fixed to said barrel and extending downwardly therefrom adjacent the forward end of said magazine tube, a forearm slidably engaged over said magazine tube, the rearward end of said forearm abutting said receiver, and the forward end thereof extending forwardly of said magazine tube and being recessed to receive said arm, a take-down screw parallel to the barrel and carried for free rotational movement in the forward extension of said forearm, a threaded portion of said screw being engageable in said arm whereby to urge said forearm rearwardly.

and to secure said barrel against rotation, said take-down screw having a rearward extension projecting within said magazine tube, and means carried by said magazine tube and operable to engage said take-down screw extension to retain the forearm in abutting relationship with respect to the receiver when said barrel has been removed from the receiver.

2. The structure as set forth in claim 1 wherein said means operable to engage said take-down screw extension comprises a spring detent supported by said magazine tube and engageable in a groove formed peripherally in said extension.

3. The structure as set forth in claim 1 wherein said means operable to engage said take-down screw extension comprises a spring detent supported by said magazine tube and engageable in a groove formed peripherally in said extension, the wall of said groove engaged by said detent being taperingly enlarged in diameter toward the rear, whereby said detent serves to urge said take-down screw rearwardly.

4. The structure as set forth in claim 1 having a plug closing the forward end of said magazine tube and secured therein, and having a socket formed therein for receiving the rearward extension of said take-down screw slidably therein, and a transverse slot formed therein intersecting said socket; said extension having a peripheral groove formed therein within said socket in registering relation with said slot, and wherein the means engageable with said extension comprises a generally V-shaped spring disposed in said slot, one leg of said spring engaging said magazine tube and the other leg being urged into said socket to engage in the groove of said screw extension.

5. The structure as set forth in claim 1 having a plug closing the forward end of said magazine tube and secured therein, and having a socket formed therein for receiving the rearward extension of said take-down screw slidably therein, and a transverse slot formed therein intersecting said socket; said extension having a peripheral groove formed therein within said socket in registering relation with said slot, and wherein the means engageable with said extension comprises a generally V-shaped spring disposed in said slot, one leg of said spring engaging said magazine tube and the other leg being urged into said socket to engage in the groove of said screw extension, said groove being V-shaped in cross-section and said spring being positioned to engage the rearward wall of said groove, whereby to urge said take-down screw rearwardly.
